CART FOR CARRYING CANS OR THE LIKE

Broadus C. Troxler, 2405 Madison Ave., Greensboro, N.C.

Filed Apr. 3, 1959, Ser. No. 55,340

Term of patent 14 years

(Cl. D14—3)

FIGURE 1 is a front perspective view of a cart for carrying cans or the like embodying my new design;
I claim:
The ornamental design for a cart for carrying cans or the like, as shown.
